UNITED STATES PATENT OFFICE.

JAMES WILSON AND JOHN STENHOUSE KEMP-WELCH, OF WANDSWORTH, ENGLAND.

PREVENTING SMOKE IN FURNACES.

SPECIFICATION forming part of Letters Patent No. 727,729, dated May 12, 1903.

Application filed August 11, 1902. Serial No. 119,243. (No model.)

To all whom it may concern:

Be it known that we, JAMES WILSON, engineer, residing at Ferrier Works, North street, and JOHN STENHOUSE KEMP-WELCH, 5 engineer, residing at Bell Lane Iron Works, Wandsworth, in the county of Surrey, England, subjects of the King of Great Britain, have invented a certain new and useful Improvement in Preventing Smoke in Furnaces, 10 of which the following is a specification.

The object of this invention is the prevention of smoke, especially when fuel is being put upon the fire. For this purpose the bridge of the furnace is hollow and contains 15 a regenerator of fire-brick or the like. When the fire is being stoked, air from the ash-pit is passed through this regenerator and mingling with the smoke consumes it. When the fire is clear, the air-supply is diminished 20 by closing a damper and gas is turned on, which by its combustion heats the regenerator.

Figures 1 and 2 are longitudinal vertical and horizontal sections of a boiler having two 25 furnaces constructed according to this invention. The upper part of Fig. 2 shows the fire-bars in place, and in the lower part they are removed. Fig. 3 is a half-section on the line 3 3, Fig. 1, and a half end elevation with the 30 door removed.

a represents the fire-bars, and *a'* the ash-pit. *b* is the hollow bridge, filled with open-work brick *c*, forming a regenerator.

d is a gas-main, and *e* represents branch 35 pipes leading from it to the regenerator.

f represents cocks on the pipes *e*. *g* is a damper admitting air to the regenerator, and *h* is a chain by which it is operated.

40 The operation of the apparatus is as follows: When the fire is burning clear in any one of the furnaces, its gas-cock *f* is opened and its damper *g* is partially closed, so as only to admit sufficient air to burn the gas entering the 45 regenerator through the cock. The combustion of the gas in the regenerator renders it intensely hot. When fuel is put on the fire, the cock *f* is closed and the damper *g* is fully opened, thereby admitting a large quantity 50 of air, which, rising up through the regener-

ator, becomes intensely hot, so that when it issues into the furnace at the bridge and comes into contact with the smoke it ignites and completely burns it. The passage of the air through the regenerator gradually cools 55 it, and when the fire has burned clear it is again heated, as above described.

The term "regenerator" is used in this specification in its ordinary sense—that is to say, a heat-reservoir, such as a mass of loose brick-work adapted to be alternately heated by combustion within it and cooled by passing air through it. The term is not intended to include externally-heated structures.

We claim—

1. In a furnace the combination of grate-bars, an ash-pit below the grate-bars, a hollow bridge having a regenerator within it over

which the products of combustion pass, means 60 for supplying gas to heat the interior of the regenerator, and means for passing air through the regenerator and into the products of combustion above the bridge when the gas is cut off.

2. In a furnace, the combination of grate-bars, an ash-pit below the grate-bars, a hollow bridge having a regenerator within it over

which the products of combustion pass, a gas-pipe leading to the regenerator and supplying 70 gas to heat the interior thereof, a damper between the ash-pit and the interior of the regenerator, and means for opening and closing the damper whereby air may pass from the ash-pit through the regenerator and into the products of combustion above the bridge. 75

3. In a furnace, the combination of the grate-bars, a hollow bridge over which the products of combustion pass, a regenerator in the bridge comprising a mass of loose brick-work having air-passages through it, means 80 for supplying gas to the interior of the regenerator to heat it, and for cutting off the supply of gas thereto, and means for passing air through the regenerator and for cutting off said air-supply, substantially as described. 85

JAMES WILSON.
JOHN STENHOUSE KEMP-WELCH.
